UNITED STATES PATENT OFFICE.

EDWARD A. GUTERMANN, OF MERIDEN, CONNECTICUT.

DESIGN FOR A CHAFING-DISH STAND.

No. 38,813.

Specification for Design.

Patented Sept. 17, 1907.

Application filed August 13, 1907. Serial No. 388,423. Term of patent 7 years.

To all whom it may concern:

Be it known that I, EDWARD A. GUTERMANN, a citizen of the United States, residing at Meriden, county of New Haven, State of Connecticut, have invented a new, original, and ornamental Design for a Chafing-Dish Stand, of which the following is a full, clear, and exact description.

My invention relates to a new, original and ornamental design for a chafing dish stand.

In the accompanying drawings, I have shown the same in perspective.

The salient feature of this design is the combination of the legs in the form of columns with recessed panels mounted on a base of the peculiar form shown.

I claim—

The ornamental design for a chafing dish stand as shown.

EDWARD A. GUTERMANN.
